ABSTRACT OF THE DISCLOSURE

The specification discloses a process for producing high octane gasoline by catalytically reforming a naphtha feed containing normal butane. The normal butane is substantially converted to isobutane in the reforming zone and the isobutane is added to the feed to the alkylation zone. Normal butane is recovered from the alkylation product and is recycled to be added to the reformer feed.

This invention relates to the production of high octane gasoline. The process of the present invention is a combination process in which normal butane recovered from an alkylation process effluent, is charged, along with petroleum naphtha, into a reforming process. The normal butane is substantially isomerized therein to isobutane which is recovered and added to the feed to the alkylation process.

When hydrocarbons boiling in the naphtha range are reformed in the presence of a dual function catalyst, a number of reactions take place, including dehydrogenation of naphthenes to the corresponding aromatics, dehydrocyclization of paraffins to aromatics, hydrocracking to lower molecular weight products, and isomerization of paraffins. The overall reaction is endothermic with a typical fuel requirement of 200,000 to 300,000 B.t.u. per barrel of feed. The extent of naphthene dehydrogenation, a very desirable reaction, is increased by high temperatures and low partial pressures of hydrogen.

Addition of normal butane to the reforming charge stock, as contemplated by this invention, results in several advantages. The normal butane is substantially isomerized in the reforming zone to isobutane, a reaction which is exothermic and reduces to a small extent the fuel requirements for interheating between reaction zones. The added butanes reduce hydrogen partial pressure which increases the rate and extent of dehydrogenation of naphthenes. This advantage is accomplished without lowering the purity of the product hydrogen since the butanes produced are easily condensed therefrom. Finally, the present invention provides isobutane feed for alkylation from normal butane, an advantage of considerable magnitude in refineries where the isobutane is not abundant.

United States Patents 2,428,417, Gary, and 2,293,705, Bloch, disclose the isomerization of normal butane to isobutane for addition to an alkylation feed, but neither of these patents shows the isomerization as an incident to naphtha reforming in a reforming zone. The Gary patent is concerned with balancing the isobutane to butylene ratio in the alkylation feed stock by obtaining additional butylene through the conversion of normal butane into isobutane by catalytic isomerization followed by the conversion of isobutane to butylene by pyrolysis. This scheme serves a system which is deficient of butylene rather than isobutane. The Bloch patent is concerned with using sulfuric acid for both the purification of the butane and for alkylation.

Cooke Patent 2,358,149 discloses a thermal reforming process which charges a light naphtha mixed with recycled C₃ and C₄ hydrocarbons. The addition of the C₃ and C₄ hydrocarbons permits operation of the process

2

under conditions which effect high yields without the heavy formation of carbon on heating units. Cooke points out that his invention is a refinement utilizing this expediency of C₃ and C₄ hydrocarbon addition which expediency was first developed by Ostergaard, Patent 2,135,014. The Ostergaard patent points out that the C₃ and C₄ hydrocarbons include both saturated and unsaturated constituents. The saturated ingredients are dehydrogenated, under the conditions of the thermal reforming, to unsaturated constituents which polymerize or alkylate. Since the present invention charges only normal butane to the naphtha stock undergoing reforming, and since the conditions of the catalytic reforming of the present invention are different from those of the thermal conversion, the added light hydrocarbon undergoes isomerization rather than dehydrogenation and polymerization.

Patent 3,003,949, Hamilton, discloses, as part of an overall scheme for producing high octane gasoline, the addition of C₄ hydrocarbons, from a reformate, to the feed to an alkylation. The patent does not teach adding normal butane, from the alkylation product, to the reformer feed.

Patent 2,288,336, Welty et al., teaches that reforming a feed containing lower boiling hydrocarbons decreases hydrogen consumption and thereby increases catalyst life. By "low boiling hydrocarbons" the Welty et al. patent means those boiling in the range between an initial boiling point of 111° F. up to between about 60 and 90 percent off at 300° F. This fraction would include no hydrocarbons lighter than C₆.

Conventionally the C₅ and lighter hydrocarbons are removed from the reformer feed. It has been found, that significant conversion of normal butane to isobutane will take place in the reforming zone to provide feed additive for charge into an alkylation reactor. The present invention is particularly advantageous where isobutane alkylation feed is in short supply.

The present invention is described as a process for producing high octane gasoline which comprises subjecting a feed to catalytic reforming in the presence of a platinum on alumina catalyst, said feed comprising a naphtha and a normal C₄ hydrocarbon stream. The normal C₄ hydrocarbon stream used in the reforming has been recovered from the product of an alkylation step which will be described below. The product recovered from the reforming step contains significant amounts of isobutane, at least a portion of which has resulted from the isomerization of the added normal butane during the catalytic reforming. The isobutane is separated from the reformate and is added to an isobutane-deficient alkylation feed. The enriched alkylation feed is then subjected to alkylation conditions to give a product which contains saturated hydrocarbons suitable for use as motor fuel components and some normal butane. Most of the normal butane has been introduced in the alkylate feed and has passed through the alkylation zone unconverted. The normal butane is separated from the alkylate and is recycled as the normal C₄ hydrocarbon stream introduced into the first step reforming of the process of this invention.

Under the conditions of the reforming step, the normal butane is substantially converted into isobutane although it would not necessarily be expected that this conversion would take place to any degree because of the short residence times of the reforming feed in the reforming zone and because of the conditions in the zone. It has been found though that even with the residence times of reforming, there is between about 30 percent to 50 percent conversion of normal butane to isobutane. This conversion provides isobutane which can be alkylated with butylene under alkylation conditions. The present

invention is, therefore, most advantageously utilized to provide isobutane for alkylation at hydrocarbon refineries which are normally deficient in isobutane.

Furthermore the conversion of the normal butane to isobutane provides certain advantages to the reforming step of the process of this invention. The isomerization is exothermic and reduces fuel requirements for inter-heating between reforming zones. With the addition of the normal butane, the hydrogen partial pressure is reduced and the rate of dehydrogenation of naphthenes and the overall extent of dehydrogenation are increased so that a reformate of improved properties is produced. This latter advantage is achieved without any lowering of the purity of the hydrogen produced since the butanes can be easily separated from the reformate gas effluent.

Suitable conditions for reforming naphtha are well known in the art and this step may comprise any known or suitable reforming procedure which utilizes a dual function catalyst. The reforming of the present invention can be applied to any hydrocarbon feed stock suitable for catalytic reforming, most preferably a light naphtha stock boiling between about 120° F. and 390° F. The catalyst used in this step is preferably any of the conventional type platinum-on-alumina catalysts which generally contain between about 0.1 to 2.0 percent platinum. Catalysts of this type are available commercially and are extensively described in the literature. The compositions may include various active forms of alumina, such as gamma, eta, and kappa, and the aluminas may vary considerably in surface characteristics depending upon how the catalyst was made. The combination of platinum and the alumina produces a catalysts having a plurality of functions whereby such reactions as dehydrogenation, isomerization, cyclization and hydrocracking are promoted. In some cases a minor amount of a halogen, such as chlorine or fluorine, is incorporated in the catalyst to control the catalytic activity for promoting certain types of these reactions.

In reforming naphtha or gasoline stocks with the catalyst the conditions can be varied rather widely; thus temperatures of about 600° to about 1050° F. are suitable and the preferred range is from about 800° to about 950° F. Within these temperature limits weight space velocities of about 0.05 to about 10.0 pounds of naphtha, per hour, per pound of catalyst in the reaction zone may be employed advantageously; however, space velocities of about 0.25 to about 5.0 provide the best results. Hydrogen should be introduced into the reforming reactor at rates running from about 0.5 to about 20.0 mols of hydrogen per mol of hydrocarbon reactants. The hydrogen is in admixture with the normal butane added in the present invention. The normal butane is added in a ratio of about 0.5 to about 5.0 mols of butane to naphtha reactant. While the total reaction pressure in the reforming may be maintained at any value between about 50 and about 1000 pounds per square inch gauge (p.s.i.g.), the best results are obtained by holding the reaction pressure within the range between about 100 and about 750 p.s.i.g. In any event, the reaction conditions should be adjusted to effect a net production of hydrogen in the reaction.

The alkylation step of the present invention can be any one of a number of alkylation processes well known in the art. This step can be a thermal alkylation at high temperatures, about 900° F., and pressures, 600 to 3000 p.s.i.g. with a contact time of about 5 minutes. However, catalytic alkylation is the preferred method for this step. This process can be conducted using either sulfuric acid or hydrogen fluoride as catalyst. In the alkylation, sulfuric acid concentration is maintained at about 90 percent and hydrogen fluoride concentrations usually are between 80 and 90 percent. With sulfuric acid, the product quality is improved with reduction in temperature to the range 32° to 50° F. A suitable temperature control can be obtained by evaporation of the reactants at the site of reaction. With hydrogen fluoride the process is less

sensitive to temperature, and temperatures of 32° to about 100° F. can be used. Some form of heat removal is essential, since the heat of reaction is approximately 600 b.t.u. per pound of butylene. In order to prevent polymerization of the butylene as charged, a large amount of isobutane should be present in the reaction zone. Isobutane-to-butylene mol ratios of 8 to 1 are common, but side reactions can be suppressed more effectively by use of larger ratios up to 14 to 1. The alkylation reaction depends on a two-phase system with a low solubility of the isobutane in the catalyst phase. In order to insure intimate contact of reactants and catalyst, efficient mixing with fine subdivision is provided.

The drawing illustrates one embodiment of the present invention. In the drawing a light naphtha is mixed with normal butane from line 18 and is fed via line 1 into the reforming zone 2. Heat input into the reforming zone is indicated at 3. A reformate containing substantial amounts of isobutane is transferred via line 4 to a high pressure separator 5 where a gaseous recycle stream is separated. The gaseous recycle is removed from the high pressure separator 5 through line 6. The reformate is transferred from the high pressure separator 5 through line 7 to a stabilizing zone 8 where the light ends are removed via line 9 to produce a stabilized reformate via line 10. C₄'s are recovered from the light ends at zone 11 with the remaining light hydrocarbons passing out line 12 and C₄'s passing via line 13, to be mixed with an alkylation feed in line 14. The alkylation feed comprises butylene and isobutane but is deficient in isobutane necessary to give best results in the alkylation zone 15. The isobutane-enriched feed and recycle isobutane from line 20 are subjected to alkylation conditions in zone 15. The alkylation effluent is removed via line 16 to zone 17 where isobutane and n-butane are recovered. Normal butane is recycled via line 18 to be admixed with the reformer feed in line 1. Isobutane is recycled to alkylation zone 15 via line 20. An alkylate boiling in the gasoline boiling range is recovered from the separator zone 17 via line 19.

The following example illustrates the invention:

A light naphtha fraction boiling between 145° and 210° F. is mixed with a normal butane stream at about 2 mols of normal butane per mol of naphtha. The mixture is fed into a reforming zone where it is contacted with platinum catalyst deposited on an eta alumina base containing about 1 percent combined fluorine. The temperature in the reformer is maintained at about 850° to 875° F. and the pressure at about 400 p.s.i.g. The liquid hourly space velocity is at about 3. Hydrogen is added to the feed in such an amount that the hydrogen to hydrocarbon mol ratio is about 7 to 1. Effluent from the reforming zone is subjected to a high pressure separation which removes gas for recycle. Liquid from the high pressure separation zone is then stabilized. Isobutane recovered from the light ends from the stabilizer are condensed and added to an alkylation feed containing isobutane and butylene in mol ratio of 5 to 1. This isobutane is added at such a rate as to give an isobutane-to-butylene mol ratio in the enriched feed of about 10 to 1. The enriched feed is fed into the alkylation zone, at a rate such as to provide a residence time of 30 minutes, where it is contacted with concentrated sulfuric acid at a temperature of about 40° F. and at a pressure slightly above atmospheric. A product, containing 23 weight percent 2,2,4 trimethylpentane and 35 percent trimethylpentanes other than 2,2,4, is recovered in the alkylate along with 3 weight percent normal butane which is recycled to be mixed with the reformer feed.

The example shows that normal butane can be isomerized to isobutane under reforming conditions and in admixture with the reforming feed. The example also shows that the isobutane recovered from the reformate can be used as make up isobutane in alkylation feed deficient in isobutane.

What is claimed is:

1. A process for producing high octane gasoline which comprises:
- (a) subjecting a feed to catalytic reforming, said feed comprising a naphtha and a hereinafter specified normal butane stream;
  - (b) recovering a reformate of improved gasoline characteristics containing isobutane at least a portion of which has resulted from the isomerization of said butane stream during said reforming;
  - (c) separating a stream containing at least a portion of said isobutane;
  - (d) charging said separated stream from step (c), mixed with an alkylation feed comprising butylene, isobutane and normal butane, into an alkylation zone under alkylation conditions to alkylate the isobutane with butylenes to obtain an alkylation product comprising saturated hydrocarbons suitable for use as a motor fuel component and normal butane;
  - (e) separating said normal butane from said alkylation product; and
  - (f) recycling said normal butane from step (e) as said normal butane hydrocarbon stream in step (a).
2. The process of claim 1 in which step (a) comprises subjecting said feed to catalytic reforming in the presence of a platinum on alumina catalyst at a temperature of about 600° to 1050° F. and at a weight space velocity of about 0.05 to about 10.0 pounds of feed per hour per pound of catalyst and with the addition of hydrogen to said reforming at a rate from about 0.5 to about 20.0 mols of hydrogen per mol of feed.
3. The process of claim 2 in which step (a) comprises

subjecting said feed to catalytic reforming in the presence of a platinum on alumina catalyst at temperatures of about 800° to 950° F. and at a weight space velocity of about 0.25 to about 5.0 pounds of feed per hour per pound of catalyst.

5   4. The process of claim 3 in which in step (d) the alkylation is carried out in the presence of a sulfuric acid catalyst.

10   5. The process of claim 3 in which in step (d) the alkylation is carried out in the presence of a hydrogen fluoride catalyst.

15   6. The process of claim 4 in which in step (d) the alkylation is carried out at temperatures between about 32° to about 50° F. and at a mol ratio of isobutane to butylene of between about 8 to 1 and about 14 to 1.

15   7. The process of claim 5 in which in step (d) the alkylation is carried out at temperatures between about 32° to about 100° F. and at a mol ratio of isobutane to butylene of between about 8 to 1 and about 14 to 1.
